The ornamental design for a footgauge touchscreen, as shown and described.

DESCRIPTION

FIG. 1 is a top view of a footgauge touchscreen according to our invention;

FIG. 2 is a right side view thereof;

FIG. 3 is a bottom view thereof;

FIG. 4 is a front view thereof;

FIG. 5 is a rear view thereof;

FIG. 6 is a perspective view thereof;

FIG. 7 is an alternative perspective view of FIG. 1; and,

FIG. 8 is a left side view of the footgauge touchscreen of FIG. 1.

The broken lines shown in the drawings illustrate portions of the footgauge touchscreen that form no part of the claimed design.
